(57) **CLAIM**

The ornamental design for an article of footwear, as shown and described.

DESCRIPTION

FIG. 1 is a perspective view of an article of footwear, showing my new design;

FIG. 2 is a right side view of the article of footwear of FIG. 1; FIG. 3 is a left side view of the article of footwear of FIG. 1; FIG. 4 is a front view of the article of footwear of FIG. 1; FIG. 5 is a rear view of the article of footwear of FIG. 1; FIG. 6 is a top plan view of the article of footwear of FIG. 1; and,

FIG. 7 is a bottom plan view of the article of footwear of FIG. 1.

The drawings show the design of an article of footwear suitable for being worn on a right foot. The ornamental design also includes the mirror images of drawings, i.e., the design of an article of footwear suitable for being worn on the left foot. The broken lines shown in the drawings represent portions of the article of footwear that form no part of the claimed design.
